UNITED STATES PATENT OFFICE.

PETER A. ARMODT, OF PHILADELPHIA, PENNSYLVANIA.

LIFE-PRESERVER.

SPECIFICATION forming part of Letters Patent No. 248,266, dated October 18, 1881.

Application filed August 22, 1881. (No model.)

To all whom it may concern:

Be it known that I, PETER A. ARMODT, a citizen of the United States of America, residing at Philadelphia, in the county of Philadelphia and State of Pennsylvania, have invented certain new and useful Improvements in Life-Preservers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a view in perspective of the device in use as a life-preserver; Fig. 2, a side elevation, showing the pocket; Fig. 3, a view in perspective, showing the device in use as a bolster as applied to the berths in the state-rooms of steamers, &c.; and Fig. 4 is plan view, partly in section, showing the manner of fastening the lower part of the device about the body.

This invention has relation to bolsters for mattresses, which may be at a moment's notice converted into a life-preserver, and so fastened or secured to the body as to prevent its becoming accidentally detached, and the novelty consists in the construction of the same, as will be hereinafter more fully described, and particularly pointed out in the claim.

In the accompanying drawings, similar letters of reference marked thereon indicate like parts of the invention.

A is a bag or pouch, made of canvas, or the like, triangular in cross-section, and filled with cork or other analogous material.

B is a similar bag, but it is provided with a water-tight pocket, C, having a flap, c. Said pocket is intended to contain valuables and the like.

To both of the upper corners of the bag A

are attached straps a, provided at their free end with a spring snap-hook, c', which catches in the ring b on the upper end of the bag B. 45 These straps a are adjusted to fit over the shoulders, as shown in Fig. 1.

To the lower end of the bag A is secured a cord, a', which passes through a ring, b', placed opposite to it on the other bag, B; thence 50 through another ring, b², on the same bag, and it is then adjustably secured to a ring, b³, on the bag A, as shown in Fig. 4.

The operation of the invention is as follows: Upon retiring at night the passenger places 55 such valuables as money, watch, and papers in the pocket C, and even should no accident happen to the boat the valuables would be far safer in a secure pocket under the bolster than in any ordinary place in the state-room in the event 60 of an attempt at robbery, for it would be almost impossible to abstract the contents of the pocket without awakening the occupant of the berth. In the event of an accident to the steamer or ship no time is lost in securing the valuables, 65 as the person has only to secure the bolster and fasten it to his body, as shown in Fig. 1, and be reasonably prepared for the emergency.

Having thus fully described my invention, what I claim as new and useful, and desire to 70 secure by Letters Patent of the United States, is—

A life-preserver consisting of the triangular or wedge-shaped bags A B, provided with the straps a a', rings b b', and cord a', and having 75 the pocket C, constructed and arranged substantially as shown.

In testimony whereof I affix my signature in presence of two witnesses.

PETER A. ARMODT.
